UNITED STATES PATENT OFFICE.

TERELIUS A. HILL, OF RICHLAND, IOWA.

GATE.

SPECIFICATION forming part of Letters Patent No. 328,118, dated October 13, 1885.

Application filed October 22, 1884. Serial No. 146,189. (No model.)

To all whom it may concern:

Be it known that I, T. A. HILL, of Rich-
land, in the county of Keokuk and State of
Iowa, have invented certain Improvements in
5 Gates, of which the following is a specifica-
tion.

This invention relates to that class of swing-
ing gates which are opened and closed and
latched and unlatched by means of hand-le-
vers located at a distance therefrom.

It consists in various peculiarities of con-
struction which are hereinafter described and
claimed.

Referring to the accompanying drawings,
15 Figure 1 is a perspective view of my gate as
it appears when closed. Fig. 2 is a vertical
longitudinal section through the rear end of
the gate on the line $x x$ of Fig. 3. Fig. 3 is a
20 cross-section of the same on the line $y y$ of
Fig. 2. Fig. 4 is a bottom plan view showing
the link and the connection of the rods there-
with for operating the latch. Fig. 5 repre-
sents a top plan and an edge view of the latch-
operating lever.

25 In proceeding to embody my invention I
first construct the rigid rectangular gate A,
consisting of a series of horizontal bars or
rails, a , firmly united at their front and rear
ends by means of vertical bars b , bolted or
30 nailed thereto. Diagonal or other braces may
be applied in any ordinary or appropriate
manner to give rigidity to the structure.

Near its end I extend the rails of the gate
35 through a swiveled post, B, the details of
which are shown in Figs. 2 and 3. This post
consists of two vertical bars, c , applied to op-
posite sides of the gate and bolted at their
upper and lower ends to journal-plates d ,
40 which are inserted between them in the man-
ner shown. Each of these plates has a jour-
nal or trunnion on its outer end, and has its
inner end curved laterally or widened in or-
der that it may be firmly connected to and
45 afford a solid bearing for the bars c . The
gate is secured within the swiveled post by
means of transverse bolts f , inserted through
its upper and lower rails, which latter are
provided with a series of holes to receive the
50 bolt, in order that by changing the bolt from
one to another the gate may be adjusted to
raise or lower its forward end.

Having provided the gate, I next erect two

vertical posts, C, and connect the same at
their upper and lower ends by means of hori-
55 zontal bars or plates $g g'$, provided with holes
to receive the trunnions of the swiveled posts
and thus give support to the gate.

It will be observed that each of the bars g
 g' is provided with a number of holes in order
60 to admit of the trunnions being shifted in such
manner as to compensate for any inclination
of the posts C and maintain the gate at all
times in a vertical position. I provide the
gate at its forward end with a pivoted gravi-
65 tating latch, E, such as shown in Fig. 1, and
provide a stationary post, F, having a catch
or keeper to engage the latch. To the rear
end of the gate I pivot a horizontally-swing-
ing angular lever, G, as plainly shown in Figs.
70 1 and 4, and connect one end of the same, by
a wire or rod, H, with the upper end of the
latch, as shown in the several figures, so that
when the lever is moved in the direction in-
dicated by the arrow in Fig. 4 it will have the
75 effect of raising the latch and releasing the
gate.

I next erect at the right side, on oppo-
site sides of the gate at a suitable distance
therefrom, inclined posts or standards I I',
80 in which I pivot upright hand-levers J J'.
From the lower end of the lever J, I extend a
rod or wire, K, to the latch-operating-lever
G, and then continue a wire, K', from said
lever to the upper end of the second hand-le-
85 ver, J'. I also extend a wire or rod, L, from
the upper end of the lever J to the lower end
of the lever J', this arrangement causing the
movement of either lever in one direction to
move the other in the opposite direction.

The operation is as follows: Assuming the 90
gate to be closed and latched, as represented
in Fig. 1, the operator approaching the same
from either side will urge the upper end of
the appropriate hand-lever in the direction
of the gate, the effect of which will be, first,
95 to cause the connecting-wires to turn the el-
bow-lever G in the direction shown by the
arrow in Fig. 4, thereby unlatching the gate,
and, second, through the lever to urge the rear
end of the gate laterally in such manner as to
100 cause the gate to swing open. After passing
the gate, the operator urges the second lever
in a direction away from the gate, the effect
of which is to cause the rods to swing the gate

to its closed position and release the latch so that it may engage the keeper.

It is to be observed that both levers are moved in the direction in which the operator travels, so that they may be actuated by those riding in carriages or on horseback without the necessity of dismounting.

It will be observed that the adjustment of the gate and the posts C by means of the pins 10 f, and the series of holes therefor provides for lifting the free end to compensate for any sag which may occur, and that the adjustment by means of the series of holes in the bars g g' will compensate for the inclination of the posts 15 C in a lateral direction.

Having thus described my invention, what I claim is—

1. In combination with the gate having the trunnions d, the posts C, located on opposite 20 sides of the gate and connected by the cross-bars g to sustain the trunnions, the latch E, the angular lever G, mounted on the rearward extension of the gate and connected with the latch, and the two levers J and J', located at 25 opposite sides of the gate and connected by the crossed wires K, K', and L with each other and with the lever G.

2. In combination with the swinging gate having trunnions d thereon, and the levers and crossed rods or wires for operating said 30 gate, the posts C C, located in the relative positions shown on opposite sides of the gate, and the cross-bars g g', connecting said posts and provided with a series of holes to admit of the positions of the trunnions being changed. 35

3. In combination with a gate provided with a series of holes, the pins f, the slotted swiveling post B, the stationary posts C, located on opposite sides of the gate and the cross-bars g g', connecting said posts and provided with a series of holes to receive the trunnions, whereby the gate may be adjusted to raise and lower its swinging end, and also adjusted to compensate for lateral inclination of the posts C. 40

In testimony whereof I hereunto set my hand, this 10th day of July, 1884, in the presence of two attesting witnesses.

TERELIUS A. HILL.
